UNITED STATES PATENT OFFICE.

OLIVER CLAUDE HANEY, OF LOS ANGELES, CALIFORNIA.

ROTARY TOOTH-BRUSH.

1,204,762.

Specification of Letters Patent.

Patented Nov. 14, 1916.

Application filed November 16, 1915. Serial No. 61,853.

To all whom it may concern:

Be it known that I, OLIVER C. HANEY, a citizen of the United States of America, and a resident of Los Angeles, in the county 5 of Los Angeles and State of California, have invented certain new and useful Improvements in Rotary Tooth-Brushes, of which the following is a specification.

This invention relates to improvements 10 in rotary brushes and more particularly to tooth brushes.

The object of the invention is to provide a simply constructed, efficient device of this character in which the parts may be readily 15 assembled and detached for cleaning and other purposes.

With this and other objects in view, the invention consists of certain novel features of construction, combination and arrangement of parts, as will be hereinafter more particularly described and claimed.

In the accompanying drawings, Figure 1 represents a side elevation of the complete brush assembled ready for use; Fig. 2 is 25 a longitudinal section thereof; Fig. 3 is a detail longitudinal section of the inner end of the outer sleeve or shell; Fig. 4 is a similar view of the connected ends of the worm rod and brush; Fig. 5 is an end elevation of 30 the brush.

In the embodiment illustrated, an outer open ended shell 1 is shown, the opening at the front end thereof being reduced as shown at 1^a and shouldered at the inner end 35 of said opening as indicated at 2 with an annular flange 3 spaced longitudinally from said shoulder 2 to form a chamber 4 for a purpose to be described.

An inner sleeve 5 is mounted to slide in 40 the shell 1 and forms a hollow plunger open at both ends, the front end thereof having a reduced angular opening 6 which is designed to receive a worm rod 7. This worm rod 7 has a threaded socket 8 at its rear end 45 in which is mounted a headed screw 9. The head of this screw 9 is substantially the same in diameter as the inner diameter of the hollow plunger or sleeve 5 and is designed to form a disk-shaped guide for said 50 plunger whereby the rod is retained in centrally disposed position therein. The front end of the rod 7 has a threaded extension 10 on the inner end of which is fixed an annular flange 11 and in advance of which 55 is arranged a connecting sleeve or coupling 12. This flange 11 is also designed to be

disposed in the chamber 4 formed between the shoulder 2 and flange 3 of the outer shell, whereby the rod is held against longitudinal movement and yet is free to rotate. This coupling sleeve 12 is about twice as long as the threaded extension 10 of the rod 7 more or less and the front end thereof is designed to receive the threaded rear end 60 of the shank or spine 14 of the cleaning brush, whereby the brush is detachably connected with the rod 7. This brush is preferably cylindrical in form with the bristles 15 thereof radiating from the spine 14 beyond its threaded rear end 13. This spine 70 14 projects at its front end beyond the bristles 15 to form a bearing 16 for turning in a suitable journal to be described.

An end cap 17 is designed to fit within the outer shell 1 and has a reduced threaded extension 18 adapted for engagement with the rear end of the inner sleeve or plunger 5 whereby said plunger is connected with said cap to provide for its reciprocation within the shell 1 by means of which rotary motion is imparted to the brush owing to the engagement of the angular opening 6 of said plunger with the worm rod 7. The cap 17 has an annular shoulder 19 which is designed to abut against the rear end of 75 the shell 1 when the parts are assembled in position as is shown clearly in Fig. 2 so that when the parts are assembled and in inoperative position, the outer shell 1 and the cap 17 will form a continuous apparently unitary structure similar in appearance to a fountain pen.

A protecting hood 20 is mounted on the front end of the shell 1, the brush incasing portion 21 of which is semi-circular in transverse section and is designed to protect the cheek of the user when the brush is in use preventing the bristles thereof from injuring the tender portions of the mouth. This hood 20 has a cylindrical inner end 22 which encircles and frictionally engages the front end of the casing 1 and is adjustably mounted thereon. The front end of this hood 20 has a journal 23 formed therein to receive the bearing 16 on the front end of the rotary brush as is shown clearly in Fig. 2 to insure the proper positioning of the brush and to prevent it from becoming deflected when in use.

From the above description, it will be 110 obvious that this brush while simple in construction, is very efficacious in use and the

parts thereof may be readily detached for cleaning or other purposes and the brush when worn may be detached from its operating worm rod and a new brush substituted without any of the other parts being changed.

I claim as my invention:

In a rotary tooth brush, a cylindrical outer casing having a reduced opening at its front end with a shoulder at the inner end of said opening, an annular member arranged inside said casing and spaced inward from said shoulder, an inner sleeve mounted to reciprocate in said outer casing and having an angular opening at its front end, a worm rod extending through said sleeve and carrying a radial flange disposed between the shoulder and annular member

in said casing, whereby said rod is held against longitudinal movement and yet permitted to rotate, said rod having a threaded extension in advance of said flange, a disk-shaped guide member adjustably mounted on the rear end of said rod, and having a sliding engagement with said inner sleeve, a brush having a threaded extension at its inner end, a sleeve connecting the extensions of said brush and rod, a cap engaged with the rear end of said first mentioned sleeve to provide an operating handle therefor, and a mouth protecting hood engaged with said outer casing and extending over said brush.

September 17, 1915.

OLIVER CLAUDE HANEY.
